(57) **CLAIM**

The ornamental design for an electronic device as shown and described.

DESCRIPTION

FIG. 1 is a front top perspective view of an electronic device showing our new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof; and,

FIG. 8 is an enlargement taken from FIG. 1 thereof.

The broken lines depict portions of the electronic device which form no part of the claimed design.

The dot-dash broken lines show an area of enlargement.

(Continued)

The black shading depicts contrast in appearance, not any particular color.

The plurality of circles to the left and right of the keyboard are shown in broken lines.
